13 Claims. (Cl. 10—122)

1

This invention relates to die stocks for use in threading tubes, bars and like work and refers to that kind of die stock which comprises a body carrying the screwing dies and means for displacing the dies towards and away from the work so that the threading can be carried out in a plurality of stages usually two stages, that is to say, the thread can initially be cut to half the proper depth, after which the thread is cut to full depth by a further screwing operation. Such an arrangement facilitates the cutting of the threads by the operator in cases where the work is of relatively large diameter, so that a fairly substantial effort on the part of the operator would be required, if the thread was initially cut to the full depth.

As hitherto constructed the dies have been mounted for radial movement in relation to the body and have been advanced towards or away from the work by means of a cam member mounted rotatably on the body and provided with a cam face adapted to engage with a further face on each of the dies so as to effect their displacement, and the cam member and the body have been provided with co-operating scale markings adapted to register when the dies are in the correct position for cutting a thread to the full depth.

With such an arrangement the position of the dies for effecting a thread cut of less than the full depth has to be estimated from scale reading, while the position for cutting the threads to the full depth is dependent upon accurate reading of the scale by the operator and if this is read inaccurately or carelessly an improper thread will result.

The primary object of the present invention is to provide an improved arrangement in which the dies are locked positively both in a position for cutting a thread to the full depth and also in an intermediate position for cutting the thread to less than the full depth.

A further object of the invention is the provision of means for rapidly displacing the dies in either of their operative positions into and out of operative engagement with the work.

A further object of the invention is the provision of a die stock in which such locking means and release means are not subjected to any appreciable thrust tending to displace them out of their operative positions in consequence of the operative engagement between the dies and the work to be threaded during the threading operation.

Other objects of the invention will be appar-

2

ent from the following description of the invention and the claims appendent thereto and the drawings accompanying the specification, in which:

5 Figure 1 is a plan view of one form of a die stock constructed in accordance with the present invention and intended for use in threading the exterior of a bar or tube.

10 Figure 2 is a side view of the same construction looking in the direction of the arrow 2—2 in Figure 1.

Figure 3 is a part sectional view on the lines 3—3 of Figure 1.

15 Figure 4 is a cross sectional view of part of the same construction illustrating the mechanism provided for varying the operative position of the dies, the mechanism being depicted in a position in which the dies are out of operative engagement with the work.

20 Figure 5 is a sectional view on the line 5—5 of Figure 4 showing the mechanism in the position in which the dies are out of operative engagement.

Figure 6 is a view similar to Figure 5 showing 25 the mechanism in a position in which the dies are in full operative engagement with the work for cutting a thread to the full depth.

Figure 7 is a view similar to Figure 6 in which 30 the mechanism is in a position such that the dies may cut a thread to half the full depth.

Referring to the drawings the die stock there illustrated comprises a hollow body 10 of cylindrical form provided at four symmetrically disposed positions with a radially extending die opening 11, in each of which is radially slidable one of the four thread cutting dies 12 which are provided, the dies being formed on their inner ends with the usual thread cutting teeth 13.

Intermediate its upper and lower ends the body 40 10 is formed with a radial outwardly extending flange 14 which terminates in an axial upwardly extending lip 15 so as to provide an annular space 16, above which is rotatably mounted an annular die displacing member 17 conveniently in the form of a plate, the under face of which near its periphery engages rotatably with the upper edge of the aforesaid lip 15, while the outer face of the die displacing member is flush with the adjacent end of the cylindrical body and is retained therein by a retaining ring 18 having a flange which screws into the interior of this end of the body.

The die displacing member is formed on its under face with four symmetrically disposed ar- 45 50 cuate shaped projections 19 which are eccentric

to the axis of rotation of the member 17 and constitute each a cam which works in a slot 20 provided transversely in the adjacent upper edge of each of the dies 12. The arrangement is such that when the member 17 is rotated in either direction the dies are advanced radially towards or retracted from the axis of the work to be threaded, which work may for instance comprise a round metal bar or a tube.

The member 17 is formed at one side with a peripheral part-circular flange 21 in which is formed an arcuate slot 22 through which projects an axially extending externally threaded guide sleeve 23, which sleeve engages the slot non-rotatably but slidably so that the die displacing member 17 can be turned relative to the guide sleeve to an extent corresponding to the length of the slot 22, the member 17 being normally releasably locked against such turning movement by a locking nut 24 on the exterior of the sleeve, the locking nut engaging the flanged part 21 of the die displacing member through the medium of a washer 25 and carrying a suitable operating arm 26.

Mounted rotatably within the interior of the guide sleeve 23 is an operating member 27 in the form of a spindle carrying at its lower end an eccentric constituted by a pin 28, the axis of which is eccentric in relation to the axis of rotation of the operating member spindle 27. The spindle 27 has limited axial movement in an upward direction in relation to the sleeve 23, which axial movement is controlled and limited by a compression spring 29 disposed in an enlarged part of the sleeve near its lower end and acting between the inner end of such part and a shoulder 30 on the spindle adjacent the eccentric pin 28.

The spindle 27 is provided at its upper end with an operating knob 31 whereby it may be rotated, but rotation of the spindle is normally prevented by providing the knob on opposite sides thereof with a pair of dependent ears 32 which normally engage in diametrically disposed recesses formed in the adjacent upper end of the sleeve 23, lifting of the knob 31 against the action of the spring 29 permitting of the knob and spindle to be rotated through 180° and relative to the sleeve 23, whereupon the ears 32 can be re-engaged in the recesses in the sleeve end so as to lock the spindle in such new position, such rotation of the spindle serving to displace the eccentric pin 28 through a distance corresponding to twice its throw.

The eccentric pin 28 works within a correspondingly shaped hole 33 provided on the inner end of a release lever 34 which is formed immediately on the outer side of such hole 33 with a second parallel hole 35 which is likewise axial with respect to the cylindrical body, and into this hole 35 extends rotatably a pivot pin 36 mounted fixedly on the outer end of a radially disposed plunger 37, which plunger is radially slidable in a pair of radially spaced slots 38, 39 formed respectively one in the cylindrical wall of the body 10 and the other in the lip 15.

The release lever 34 is hollow intermediate the pivot pin 36 and the outer end 40 of the lever, and is provided internally with a compression spring 41 acting between a screw 42 at the outer end, and a detent in the form of a ball 43, which engages with one of a pair of recesses 43a, spaced circumferentially around the pivot pin so as to locate the release lever 34 in either of two positions, namely a release position depicted in Figures 4 and 5 in which the lever is radial with respect to the body and work axis as well as in a

die locking position depicted in Figures 6 and 7 in which the lever is more or less tangential relative to the body and in which the dies are in operative engagement with the work.

Means are provided for rotating the body of the die stock about the axis of the work to be threaded, such means comprising a die stock rotating member 44 of annular form which extends around the exterior of the body 10 intermediate the upper and lower ends thereof, the rotating member being operatively connected to the body by means of one way ratchet mechanism of known form indicated generally at 45 in Figure 3 and being provided with a pair of diametrically opposed sockets 46 for the reception of turning bars, the inner ends of which are indicated at 47 in Figure 1.

Centering means of known form comprising a plurality of symmetrically disposed radially slid-
20 able centering elements 48 are further provided, such elements being adapted at their inner ends to engage rotatably with the exterior of the work below the part to be threaded and being capable of being displaced radially in the known manner
25 by a ring 49 mounted rotatably on the lower end of the die body, the ring having a threaded connection indicated at 50 with the elements 48 and being capable of being turned by handle 51.

The upper face of the die displacing member
30 17 and the retaining ring 18 forming part of the body 10 are provided with setting markings indicated generally at 52, which markings indicate the relative position of the die displacing member 17 and the body for the cutting to the full
35 depth of screw threads appropriate to the external diameter of the work which is being operated on.

In the aforementioned description the expressions "upper" and "lower" where used are employed merely to denote that part of the die stock which is situated nearest and furthest respectively from the threading dies.

The mode of operation of a die stock constructed as above described is as follows. The arm 26 which serves to lock the threaded guide sleeve 23 and spindle 27 to the die displacing member 17 is initially released thereby permitting of the die displacing member being pivoted relative to the body 10 until the appropriate setting markings of the dies for the particular work to be threaded are opposite to one another on the die displacing member 17 and the ring 18, and the operating arm 26 is then actuated to lock the die displacing member 17 in this position to the guide sleeve 23 and hence to the spindle 27.

The release lever 34 is then displaced into the release position illustrated in Figures 4 and 5 so as to displace the dies radially outwardly into a position in which they are incapable of operative engagement with work of external diameter corresponding to the above setting of the die displacing member.

Assuming that it is now desired to cut the threads initially to half the full depth the operating knob 31 is actuated to displace the spindle 27 axially of the sleeve 23, so as to disengage the ears 32 from the recesses in the upper end of the sleeve 23 and permit of the spindle being turned into a position corresponding to the half depth 70 thread cutting position of the dies.

Such position is conveniently readily observable by providing the upper face of the knob 31 with the markings "full" and "half," so that when the release lever 34 is on the operator's left hand 75 and the word "half" appears in a readable po-

sition, the dies are in the appropriate position for cutting the threads to the half depth, while with the spindle rotated through 180° so that the word "full" appears in a readable position as shown in Figure 1, the dies are in the position for cutting threads to the full depth.

With the spindle 27 adjusted to the half cutting position the die stock is disposed over the end of the work to be threaded with the dies opposite to the particular part of the work upon which the threads are to be cut and the elements 48 are brought into guiding engagement with the exterior of the work below the part to be threaded.

The release lever 34 is now displaced from the release position depicted in Figures 4 and 5 to the operative position depicted in Figures 6 and 7 such movement serving to bring the eccentric pin 28 and operating spindle 27 from a position in which they are situated on the radially inner side of the pivot pin 36 to a position in which the eccentric 33 together with the axis of the spindle 27 are spaced substantially circumferentially with respect to the pivot pin 36. Owing to the fact that the spindle 27 can only move bodily about the axis of rotation of the body, in consequence of this movement of the release lever the pivot pin 36 is constrained to move radially inwardly during such movement of the release lever as is permitted by the radially slideable mounting of the plunger 37.

As will be apparent from a consideration of Figures 5, 6 and 7 the release lever during such movement turns about the pivot pin 36 through an angle of approximately 90°. As the pivot pin 36 is constrained to be displaced bodily in a radial direction by the plunger 37, the operating spindle 27 is displaced in a circumferential direction by a distance corresponding substantially to the distance between the axis of the spindle and the axis of the pivot pin 36 and a corresponding pivotal movement of the die displacing member 17 is effected by reason of the fact that the guide sleeve 23 carrying the spindle is locked to the member 17. In consequence of this displacement of the member 17 the cams 19 thereon effect operative displacement of the dies in an inward direction so as to bring them into the half thread depth cutting position.

Threading of the work to half depth is now effected by rotating the die stock bodily in the known way.

When the desired axial length of thread to half depth has been cut the die stock is turned in the opposite direction back to its initial threading position in relation to the work and the operating spindle 27 is turned through 180° in relation to the sleeve 23 so as to bring it into a position corresponding to that of full thread depth.

Such movement of the operating spindle 27 serves to displace the axis of the spindle bodily in a circumferential direction relative to the axis of the eccentric pin 28 which during such movement of the spindle pivots within the hole 33 in the inner end of the release lever so that the axis of the spindle is brought from a position in which as shown in Figure 7 it is situated substantially between the axes of the eccentric pin 28 and pivot pin 36 to a position in which as shown in Figure 6 the axis of the operating spindle is disposed on the side of the eccentric pin axis which is remote from the axis of the pivot pin. In other words, the spindle 27 is displaced bodily in a circumferential direction between the two cutting positions by a distance

corresponding substantially to twice the eccentricity of the eccentric pin 28, thereby pivoting the die displacing member 17 relative to the release lever 34 and relative to the body 10 by a distance sufficient to cause the cams 19 to displace the dies 12 inwardly into a position for cutting the threads to the full depth, whereupon the above described threading operation is repeated to obtain the finished threads on the work to the full depth desired.

The release lever 34 is then pivoted from an operative position to the release position thus pivoting the die displacing member 17 in the reverse direction from the position depicted in Figure 6, to that depicted in Figure 5 and bringing the dies completely out of operative engagement with the work, whereby the die stock may be rapidly removed from the work by a simple axial movement.

The maximum circumferential displacement of the operating spindle 27 in consequence of its rotation through 180° is ensured by so displacing the ears 32 on the operating knob 27 in relation to the eccentric pin 28 as to ensure that with the release lever in the operating position shown in Figures 6 and 7 and ears 32 in engagement with the recesses in the end of the sleeve 23, the axes of the eccentric pin, pivot pin 36 and spindle 27 are substantially in line, which line in fact is circumferential with respect to the axis of rotation of the die displacing member.

The distance between the axis of the pivot pin 36 and the axis of the eccentric pin 28 is made greater than the distance corresponding to twice the throw of the eccentric pin 28, thereby ensuring that when the lever 34 is displaced from one to the other of its two positions the pivotal movement of the die displacing member 17 is more than twice the movement obtained by merely rotating the spindle 27 between the two thread cutting positions of the dies.

By constructing the parts so that with the release lever 34 in the operative position the axes of the spindle 27, eccentric pin 28 and pivot pin 36 all lie substantially on a line which is circumferential with respect to the axis of pivoting of the die displacing member 17, any resultant force produced by the reaction during threading between the dies 12 and the die displacing member 17 tending to pivot these relative to the body 10 acts on the pivot pin 36 in a direction at right angles to the direction of sliding of the plunger 37 so that there is no resultant force tending to displace this radially. Furthermore, any such force tending to pivot the member 17 which acts on the eccentric pin 28 is not transmitted to any appreciable degree to the operating spindle 27 so as to tend to rotate it, by virtue of the fact that the axes of the pin 28 and spindle 27 are situated on a line which is circumferential in respect to the axis of rotation of the die displacing member 17.

Thus both the release mechanism and the die locking mechanism may be made of relatively light construction and are not subjected to appreciable stresses in consequence of the actual threading operation.

Thus there is provided a construction in which the dies are positively locked by the operating member in the two thread cutting positions and no careful observance of a scale is required on the part of the operator when cutting to less than full thread depth, it being necessary merely to actuate this member in the manner described

after cutting to half depth for the purpose of effecting the final cutting of the threads to full depth.

It is thus ensured that the threads are always cut exactly to the half and full depths required so that the construction is quite fool proof.

What I claim then is:

1. A die stock for use in forming a screw thread comprising in combination a hollow body, means for rotating said body about the axis of the work to be threaded, a plurality of threading die elements mounted on said body for movement relative to said body towards and away from the axis of rotation of the body, a die element displacing member mounted on said body for pivotal movement relative to said body, means operatively connecting said displacing member to the die elements, an operating member carried by said die displacing member so as to pivot therewith relative to the body, said operating member being mounted for rotary movement relative to the displacing member, an eccentric on said operating member, a plunger member mounted on the body for sliding movement relative to the body in a direction transverse to the direction of movement of the operating member when pivoted with the die displacing member, a die element release lever mounted for pivotal movement relative to said plunger, means for releasably locking said lever relative to said plunger, said lever having an opening therein spaced along the length of said lever relative to said lever pivot, said eccentric working within said opening in said lever, and means adapted to positively and releasably lock said operating member in either of two rotational positions in relation to the die element displacing member so as positively to lock said displacing member with its die elements in a position for cutting a thread to the full depth and also in an intermediate position for cutting the thread to less than the full depth.

2. A die stock for use in forming a screw thread comprising in combination a hollow body, means for rotating said body about the axis of the work to be threaded, a plurality of threading die elements mounted on said body for movement relative to said body towards and away from the axis of rotation of the body, a die element displacing member mounted on said body for pivotal movement relative to said body, about the axis of rotation thereof, means operatively connecting said displacing member to the die elements, an operating spindle carried by said die displacing member so as to pivot therewith relative to the body, said operating spindle being mounted for rotary movement relative to the displacing member about an axis parallel to the axis of rotation of the body, an eccentric on said operating spindle, a plunger member mounted on the body for sliding movement radially of said body axis of rotation, a die element release lever mounted for pivotal movement relative to said plunger, means for releasably locking said lever relative to said plunger, said lever having an opening therein spaced along the length of said lever relative to said lever pivot, said eccentric working within said opening in said lever, and means adapted to positively and releasably lock said operating spindle in either of two rotational positions in relation to the die element displacing member so as positively to lock said displacing member with its die elements in a position for cutting a thread to the full depth and also in an intermediate

position for cutting the thread to less than the full depth.

3. A die stock for use in forming a screw thread comprising in combination a hollow body, means for rotating said body about the axis of the work to be threaded, a plurality of threading die elements mounted on said body for movement relative to said body towards and away from the axis of rotation of the body, a die element displacing member mounted on said body for pivotal movement relative to said body about the axis of rotation thereof, means operatively connecting said displacing member to the die elements, a sleeve carried by said displacing member so as to pivot therewith relative to the body, said sleeve extending parallel to the axis of rotation of said body, an operating spindle mounted for rotation within said sleeve, an eccentric on said operating spindle and working within a bearing associated with the body, said sleeve having locking means engageable with further locking means on said operating spindle to lock the spindle against rotation relative to said sleeve, said spindle being displaceable axially of the sleeve to effect disengagement of said locking means, spring means releasably retaining said spindle in its locked position, said locking means serving to lock said spindle in either of two rotational positions in relation to the die element displacing member so as positively to lock said displacing member with its die elements in a position for cutting a thread to the full depth and also in an intermediate position for cutting the thread to less than the full depth.

4. A die stock for use in forming a screw thread comprising in combination a hollow body, means for rotating said body about the axis of the work to be threaded, a plurality of threading die elements mounted on said body for movement relative to said body towards and away from the axis of rotation of the body, a die element displacing member mounted on said body for pivotal movement relative to said body about the axis of rotation thereof, means operatively connecting said displacing member to the die elements, a sleeve carried by said displacing member so as to pivot therewith relative to the body, said sleeve extending parallel to the axis of rotation of said body, an operating spindle mounted for rotation within said sleeve, an eccentric on said operating spindle, a plunger member mounted on the body for sliding movement radially of said body axis of rotation, a die element release lever mounted for pivotal movement relative to said plunger, means for releasably locking said lever relative to said plunger, said lever having an opening therein spaced along the length of said lever relative to said lever pivot, said eccentric working within said opening in said lever, said sleeve having locking means engageable with further locking means on said operating spindle to lock the spindle against rotation relative to said sleeve, said spindle being displaceable axially of the sleeve to effect disengagement of said locking means, spring means releasably retaining said spindle in its locked position, said locking means serving to lock said spindle in either of two rotational positions in relation to the die element displacing member so as positively to lock said displacing member with its die elements in a position for cutting a thread to the full depth and also in an intermediate position for cutting the thread to less than the full depth.

5. A die stock for use in forming a screw thread comprising in combination a hollow body, means

for rotating said body about the axis of the work to be threaded, a plurality of threading die elements mounted on said body for movement relative to said body towards and away from the axis of rotation of the body, a die element displacing member mounted on said body for pivotal movement relative to said body about the axis of rotation thereon, means operatively connecting said displacing member to the die elements, said die element displacing member having an arcuate slot centred on the axis of rotation of said body, a sleeve mounted in said slot so as to pivot with said displacing member relative to the body, said sleeve being adjustable along the length of said slot, means for releasably locking said sleeve in any position along the slot relative to the displacing member, said sleeve extending parallel to the axis of rotation of said body, an operating spindle mounted for rotation within said sleeve, an eccentric on said operating spindle, a plunger member mounted on the body for sliding movement radially of said body axis of rotation, a die element release lever mounted for pivotal movement relative to said plunger, means for releasably locking said lever relative to said plunger, said lever having an opening therein spaced along the length of said lever relative to said lever pivot, said eccentric working within said opening in said lever, and means adapted to positively and releasably lock said operating spindle in either of two rotational positions in relation to the die element displacing member so as positively to lock said displacing member with its die elements in a position for cutting a thread to the full depth and also in an intermediate position for cutting the thread to less than the full depth.

6. A die stock for use in forming a screw thread comprising in combination a hollow body, means for rotating said body about the axis of the work to be threaded, a plurality of threading die elements mounted on said body for movement relative to said body towards and away from the axis of rotation of the body, a die element displacing member mounted on said body for pivotal movement relative to said body about the axis of rotation thereof, means operatively connecting said displacing member to the die elements, said die element displacing member having an arcuate slot centred on the axis of rotation of said body, a sleeve mounted in said slot so as to pivot with said displacing member relative to the body, said sleeve being adjustable along the length of said slot, means for releasably locking said sleeve in any position along the slot relative to the displacing member, said sleeve extending parallel to the axis of rotation of said body, an operating spindle mounted for rotation within said sleeve, an eccentric on said operating spindle, a plunger member mounted on the body for sliding movement radially of said body axis of rotation, a die element release lever mounted for pivotal movement relative to said plunger, means for releasably locking said lever relative to said plunger, said lever having an opening therein spaced along the length of said lever relative to said lever pivot, said eccentric working within said opening in said lever, said sleeve having locking means engageable with further locking means on said operating spindle to lock the spindle against rotation relative to said sleeve, said spindle being displaceable axially of the sleeve to effect disengagement of said locking means, spring means releasably retaining said spindle in its locked position, said locking means

serving to lock said spindle in either of two rotational positions in relation to the die element displacing member so as positively to lock said displacing member with its die elements in a position for cutting a thread to the full depth and also in an intermediate position for cutting the thread to less than the full depth.

7. A die stock for use in forming a screw thread comprising in combination a hollow body, means for rotating said body about the axis of the work to be threaded, a plurality of threading die elements mounted on said body for movement relative to said body towards and away from the axis of rotation of the body, a die element displacing member mounted on said body for pivotal movement relative to said body about the axis of rotation thereof, means operatively connecting said displacing member to the die elements, said die element displacing member having an arcuate slot centred on the axis of rotation of said body, a sleeve mounted in said slot so as to pivot with said displacing member relative to the body, said sleeve being adjustable along the length of said slot, means for releasably locking said sleeve in any position along the slot relative to the displacing member, said sleeve extending parallel to the axis of rotation of said body, an operating spindle mounted for rotation within said sleeve, an eccentric on said operating spindle, a plunger member mounted on the body for sliding movement radially of said body axis of rotation, a pivot pin on the outer end of said plunger extending transversely thereto and rigid therewith, a hollow die element release lever mounted on said pivot pin, a spring loaded detent within said lever adapted to engage with said pivot pin and lock the lever in an operative position, said lever having an opening therein spaced along the length of said lever relative to said lever pivot, said eccentric working within said opening in said lever, said sleeve having locking means engageable with further locking means on said operating spindle to lock the spindle against rotation relative to said sleeve, said spindle being displaceable axially of the sleeve to effect disengagement of said locking means, spring means releasably retaining said spindle in its locked position, said locking means serving to lock said spindle in either of two rotational positions in relation to the die element displacing member so as positively to lock said displacing member with its die elements in a position for cutting a thread to the full depth and also in an intermediate position for cutting the thread to less than the full depth.

8. A die stock for use in forming a screw thread comprising in combination a hollow body, means for rotating said body about the axis of the work to be threaded, a plurality of threading die elements mounted on said body for movement relative to said body towards and away from the axis of rotation of the body, a die element displacing member mounted on said body for pivotal movement relative to said body about the axis of rotation thereof, means operatively connecting said displacing member to the die elements, an operating spindle carried by said die displacing member so as to pivot therewith relative to the body, said operating spindle being mounted for rotary movement relative to the displacing member about an axis parallel to the axis of rotation of the body, an eccentric on said operating spindle, a plunger member mounted on the body for sliding movement radially of said body axis of rotation, a die element release lever mounted for

pivotal movement relative to said plunger, means for releasably locking said lever relative to said plunger, said lever having an opening therein spaced along the length of said lever relative to said lever pivot, said eccentric working within said opening in said lever, means adapted to positively and releasably lock said operating spindle in either of two rotational positions in relation to the die element displacing member so as positively to lock said displacing member with its die elements in a position for cutting a thread to the full depth and also in an intermediate position for cutting the thread to less than the full depth, said release lever being adapted in one pivotal position relative to said plunger and said operating spindle to secure the die element displacing member in a position in which the dies are adapted operatively to engage with the work, said operating spindle in either of its operative positions, said pivot between the release lever and the plunger, and said eccentric in either operative position of said spindle having their axes disposed on a line circumferential with respect to the axis of the body.

9. A die stock for use in forming a screw thread, comprising in combination a hollow body element, means for rotating said body element about the axis of the work to be threaded, a plurality of threading dies mounted on said body element for movement relative to said body element towards and away from the axis of rotation of the body element, a cam element mounted rotatably on said body element and having cam engagement with said threading dies so as to displace the same towards and away from the axis of rotation of the body element, a die release lever mounted pivotally on a pivot member carried by one of said two elements, said lever being operably connected to the other element so that said lever is adapted to be turned about said pivot member to displace said cam and body elements relatively between die operating and die release positions for the purpose of immediately effecting displacement of the dies into and out of operative position in relation to the work, means independent of said die release lever for displacing said pivot member bodily in relation to the element on which it is mounted and between two operative positions corresponding to different predetermined thread cutting depths, said lever being adapted to co-act with said pivot member in transmitting said bodily movement of said pivot member to displace said body and cam elements relatively between two operative positions, and means for locking said pivot member against bodily displacement in relation to the element on which it is mounted in each of said two operative positions.

10. A die stock for use in forming a screw thread, comprising in combination a hollow body element, means for rotating said body element about the axis of the work to be threaded, a plurality of threading dies mounted on said body element for movement relative to said body element towards and away from the axis of rotation of the body element, a cam element mounted rotatably on said body element and having cam engagement with said threading dies so as to displace the same towards and away from the axis of rotation of the body element, an operating member mounted upon the cam element for pivotal movement relative thereto about an axis parallel to, but spaced from the axis of rotation of the cam element on the body element, a pivot pin carried by said operating member hav-

ing its axis parallel, but eccentric to the axis of pivoting of said operating member, a die release lever mounted pivotally on the pivot pin, said die release lever being operatively connected to the body element so that said lever is adapted to be turned about said pivot pin to displace said cam and body elements relatively between die operating and die release positions for the purpose of immediately effecting displacement of the dies into and out of operative position in relation to the work, said operating member being adapted when pivoted in relation to the cam element upon which it is mounted, to displace said pivot pin bodily in relation to the cam element between two operative positions corresponding to different predetermined thread cutting depths, said die release lever being adapted to co-act with said pivot pin in transmitting said bodily movement thereof to displace said body and cam elements relatively between said two operative positions, and means for locking said operating member against pivotal movement relative to the cam element in each of said two operative positions.

11. A die stock for use in forming a screw thread, comprising in combination a hollow body element, means for rotating said body element about the axis of the work to be threaded, a plurality of threading dies mounted on said body element for movement relative to said body element towards and away from the axis of rotation of the body element, a cam element mounted rotatably on said body element and having cam engagement with said threading dies so as to displace the same towards and away from the axis of rotation of the body element, an operating member mounted upon the cam element for pivotal movement relative thereto about an axis parallel to, but spaced from the axis of rotation of the cam element on the body element, a pivot pin carried by said operating member having its axis parallel, but eccentric to the axis of pivoting of said operating member, a plunger at the side of said body element adjacent said operating member and mounted slidably on said body element for movement in a direction transverse to the direction of movement of said operating member when the cam element is pivoted on the body element, a die release lever mounted pivotally on the pivot pin, said die release lever being pivoted to said plunger for pivotal movement about an axis parallel to, but spaced from the axis of pivoting of the plunger relative to the pivot pin so that said lever is adapted to be turned about said pivot pin to displace said cam and body elements relatively between die operating and die release positions for the purpose of immediately effecting displacement of the dies into and out of operative position in relation to the work, said operating member being adapted when pivoted in relation to the cam element upon which it is mounted, to displace said pivot pin bodily in relation to the cam element between two operative positions corresponding to different predetermined thread cutting depths, said die release lever being adapted to co-act with said pivot pin in transmitting said bodily movement thereof to displace said body and cam elements relatively between said two operative positions, and means for locking said operating member against pivotal movement relative to the cam element in each of said two operative positions.

12. A die stock for use in forming a screw thread, comprising in combination a hollow body element, means for rotating said body element about the axis of the work to be threaded, a plu-

rality of threading dies mounted on said body element for movement relative to said body element towards and away from the axis of rotation of the body element, a cam element mounted rotatably on said body element and having cam engagement with said threading dies so as to displace the same towards and away from the axis of rotation of the body element, a sleeve mounted on said cam element having its axis parallel to the axis of rotation of said cam element on said body element, said sleeve being slideable bodily relative to said cam element about the axis of rotation of said cam element, said sleeve being held against rotation about its own axis relative to the cam element, means for releasably locking said sleeve against bodily sliding movement in relation to said cam element, an operating spindle pivotally mounted within said sleeve, a pivot pin carried by said operating spindle having its axis parallel, but eccentric to the axis of pivoting of said operating spindle, a die release lever mounted pivotally on the pivot pin, said die release lever being operatively connected to the body element so that said lever is adapted to be turned about said pivot pin to displace said cam and body elements relatively between die operating and die release positions for the purpose of immediately effecting displacement of the dies into and out of operative position in relation to the work, said operating spindle being adapted when pivoted in relation to the cam element upon which it is mounted, to displace said pivot pin bodily in relation to the cam element between two operative positions corresponding to different predetermined thread cutting depths, said die release lever being adapted to co-act with said pivot pin in transmitting said bodily movement thereof to displace said body and cam elements relatively between said two operative positions, said operating spindle and said sleeve having inter-engageable abutments adapted to secure the spindle against pivotal movement in relation to the sleeve so as to lock the pivot pin against bodily displacement relative to the cam element in each of said two operative positions, said spindle being axially displaceable in relation to said

sleeve for the purpose of effecting disengagement between the inter-engageable abutments so as to permit of the spindle being turned relative to the sleeve and the pivot pin displaced bodily between its two operative positions, and spring means acting between the spindle and the sleeve for retaining the said abutments in releaseable engagement with one another.

13. In a die stock for use in forming a screw thread, and of the kind comprising a hollow body, a plurality of threading die elements each displaceably mounted on the body for movement towards and away from the axis of rotation of the die stock, a die displacing element mounted rotatably on said body with cam means operating between said die displacing element and said threading die elements, the provision of a reaction member mounted slidably on the body for movement towards and away from the axis of rotation of the die elements, displacing member means releasably connecting said die elements displacing member to said reaction member, means adapted positively to lock said die elements in two positions in relation to the said die stock axis, namely, a position for cutting a thread to the full depth and also in an intermediate position for cutting a thread to less than the full depth, and said connecting means being adapted to transmit any reaction of the die elements on the die displacing member directly to said reaction member in each of said two positions of said die elements.

ARTHUR TREVENA.
